UNITED STATES PATENT OFFICE.

EDWARD A. CHRISTOPH AND EDWARD T. MUELLER, OF CHICAGO, ILLINOIS.

SHARPENING DEVICE.

1,165,750.

Specification of Letters Patent. Patented Dec. 28, 1915.

Application filed August 20, 1915. Serial No. 46,407.

To all whom it may concern:

Be it known that we, EDWARD A. CHRISTOPH and EDWARD T. MUELLER, citizens of the United States, residing at Chicago, in the county of Cook and State of Illinois, have invented a certain new and useful Improvement in Sharpening Devices, of which the following is a full, clear, concise, and exact description, reference being had to 10 the accompanying drawings, forming a part of this specification.

Our invention relates to means for sharpening knives, scissors, etc., and has for its object the provision of a household article 15 which may readily be used by an inexperienced person and which operates effectively to secure the desired results.

Our invention is illustrated in the accompanying drawings, in which:

20 Figure 1 is a side elevational view thereof, showing the application of a knife thereto; Fig. 2 is an end elevational view thereof; Fig. 3 is an elevational view of the other side; Fig. 4 is a sectional view taken on the 25 plane of the line 4—4 of Fig. 1 and looking in the direction indicated by the arrows; and Fig. 5 is a detail view of a spring device which we shall refer to.

The abrasive parts of the sharpener of our 30 invention comprise two elements in the shape of wheels 6 and 7 of emery, carborundum, or some other abrasive material. The inner face of the wheel 7 is dished, as illustrated in Fig. 4, and the inner face of the 35 wheel 6 fits in and cooperates with this dished face of the wheel 7, as clearly shown in Fig. 4. The inner face of the wheel 7 is also beveled outwardly at 8, so as to form a V-shaped groove 9 between the two members. The two wheels 6 and 7 are mounted 40 upon a screw-shaft 10, the wheel 6 directly and the wheel 7 through the intervention of an eyelet 11, which secures a ratchet-wheel 12 to the outer face thereof. The screw-shaft 10 is mounted in the two limbs of the 45 U-shaped handle 13, and a nut 14 engages the outer end of the screw so as to clamp the arrangement together. A cup spring-washer 15 which, as illustrated in Fig. 5, 50 is provided with radial slots 16, is slipped over the screw 10 between the outer face of the wheel 6 and the adjacent limb of the handle 13, as illustrated in the drawings, in order to maintain the proper bearing 55 contact between the two abrasive elements. A pawl 17 is pivoted upon an eyelet 18 set

in the limb of the U-shaped handle on the side of the wheel 7, this pawl engaging with the ratchet 12, as illustrated clearly in Fig. 1.

60 The operation of our device will now be clear. It will be evident that the wheel 7 may turn in the direction of the arrow X (Fig. 1), but not in the opposite direction. The blade of a knife is forced down into the groove 9 and it will be seen that there will always be a tension forcing the two faces of the groove together against the sides of the knife-blade. The knife is inserted between the two limbs of the U- 65 shaped handle from the left (Fig. 1) and it will be seen that in moving the knife to the right the wheel 7 will be moved therewith, the wheel 6 also moving therewith by reason of its engagement with the knife and with 70 the wheel 7. We may say here that if the two wheels are not separated by the knife-blade the connection between the two is similar to that of a cone clutch. When they are separated there is still a connection, by 75 way of the knife-blade on one side and direct on the other. In drawing the knife in the opposite direction, however, the wheels remain stationary and the proper abrasive effect of the wheels upon the knife- 80 blade is secured. The sharpening of the 85 knife is thus secured by setting the knife in the groove 9, pressing downwardly thereon to the proper extent, and moving the blade forwardly and back as rapidly as desired.

We provide in the U-shaped handle 13 two sets of slots 19, 19 and 20, 20. Each 90 set is adapted for the reception of a scissors-blade, in the manner illustrated in dotted lines in Fig. 3, the blade to be sharpened by moving it back and forth in the guiding slots so that its face may rub against the surface of the wheels 6 and 7. It will be clear that with such an engagement the scissors will be hollow-ground and that either of the sets of slots will be equally efficient to this end. In this way the structure may be used for the double purpose of grinding by means of the groove between the two 10 wheels, and also by means of the periphery of the wheels, without in any way adding to the complexity of the structure. It will appear, furthermore, that the structure which we provide is one of simple design and a 11 minimum number of parts, it being apparent that the metallic parts may all be

readily constructed by punch-press operation, except for the bolt which is employed and which is standard.

We claim:

- 5 1. In a knife sharpener, a handle, a rotatable grinding element, having a peripheral cutting groove therein and adapted to be rotated by the reciprocating application thereto of the article to be sharpened, and means for permitting movement of said element in one direction but preventing movement in the opposite direction.
- 10 2. In a knife sharpener, a handle, a pair of rotary grinding wheels having a cutting groove therebetween, said grinding wheels being adapted to be rotated by the reciprocating application thereto of the article to be sharpened, and means for permitting movement of said grinding wheels in one direction but preventing movement in the opposite direction.
- 15 3. In a knife sharpener, a handle, a rotary grinding wheel having a dished center and a beveled edge on one face, another grinding wheel having a face fitting into said
- 20
- 25

dished center, and means for permitting movement of said grinding wheels in one direction but preventing movement in the opposite direction.

4. In a knife sharpener, a handle, a rotary grinding wheel having a dished center and a beveled edge on one face, another grinding wheel having a face fitting into said dished center a ratchet wheel secured to one of said wheels and a pawl pivoted to said handle and engaging said ratchet wheel.

5. In combination, a handle, and a rotary grinding element mounted thereon, said handle having a slot in proximity to the periphery of said grinding element.

6. In combination a U-shaped handle, and a rotary grinding element mounted between the limbs thereof, said handle having laterally aligned slots in proximity to the periphery of said grinding element.

In witness whereof, we hereunto subscribe our names this 18th day of August A. D. 1915.

EDWARD A. CHRISTOPH.
EDWARD T. MUELLER.
